VAPOR AND FOG GENERATION
Edward F. Andrews, 105 15th St., Belleair Beach, Fla.
Filed Apr. 3, 1961, Ser. No. 100,060
16 Claims. (Cl. 252—359)

This application is a continuation-in-part of my pending patent application, Serial No. 595,738, filed July 3, 1956 now Patent No. 3,037,939 issued June 5, 1962. I call attention also to my Patent No. 2,765,578, issued October 9, 1956, which contains generally similar subject matter.

My invention relates to means and a method of vapor generation and for producing a thermal aerosol or fog for purposes of concealment, for controlling atmospheric temperature, for disseminating insecticide or other materials into the outside atmosphere or confined spaces, etc.

Apparatus covered by my invention is well adapted to producing heated vapor under pressure by means requiring little or no mechanical power which is of particular advantage in connection with portable applications.

It is an object of my invention to provide means and a method for vapor and/or aerosol generation requiring little or no mechanical power which is simple and economical and otherwise advantageous.

It is a more specific object to generate a fog or aerosol with light, highly portable apparatus which is well adapted to be made in small manually portable form as well as in large units of higher output.

It is a further object to generate a thermal aerosol in such a way as to minimize the exposure of heat-sensitive material to excessive temperature and to reduce the time of exposure thereto.

It is a still further object to provide an improved fogger which is a complete unit except for tanks, connecting lines and electrical connections to supply the pump motor and automatic control and protective systems.

It is a further object to improve the functioning efficiency and protection of apparatus of this type.

It is a further object to improve the functioning and equalize the oil distribution of the jet nozzle and establish improved relations of the jet nozzle relative to the fog outlet to produce improved atomization, increased ejector action, effect desired cooling and facilitate the removal and cleaning of nozzle parts and otherwise guard against nozzle obstruction.

It is a further object to improve the flow of combustion air through the device so as to eliminate heat losses, reduce exterior heating and improve its functioning and its efficiency.

My invention may take the form of a double-walled duct through which a flow of hot gases is established by means later to be described. Fuel under pressure from its own evaporation or pressurized by other means is supplied to a burner. A vaporizable liquid which may be water, oil, etc., is vaporized in a boiler inside the duct. The vapor under pressure issues from a jet nozzle connected to the boiler and may augment and mix with the flow of hot gases from said duct to form a fog jet with or without insecticide or other material. The insecticide or other material may be introduced through the jet nozzle as subsequently more fully described.

Still further objects and advantages of my invention will be made apparent in the following drawings and description.

In the drawings:

FIG. 1 is a longitudinal cross section of the complete main unit of a fogger adapted for operation on fuels requiring a specially heated vaporizer;

2

FIG. 2 is a cross section taken on the line 2—2 of FIG. 1;

FIG. 3 is a cross section taken on the line 3—3 in FIG. 1;

5 FIG. 4 is a detail of the male portion of a quick disconnect fitting equipped with a liquid metering orifice at one end;

10 FIG. 4a is a sectional view of the female portion of the quick disconnect fitting adapted for installation on a flexible compression hose and further adapted to engage the male fitting of FIG. 4;

FIG. 5 is a partial cross section of the jet nozzle and air tube assembly showing its position in the outlet cone of FIG. 1;

15 FIG. 6 is a cross section on the line 6—6 of FIG. 5;

FIG. 7 is a diagrammatic view of the fogger unit of FIG. 1 showing the fuel, water and fog material supply and the pump operated from the engine of the vehicle upon which the fogger is mounted;

20 FIG. 8 shows an embodiment of the invention in which the vaporizer of the main unit of FIG. 1 has oil or other similar liquid supplied to it by a pump and in which the same pump may supply the same liquid to the burner as fuel;

25 FIG. 8a shows a modification of the main fogger unit of FIG. 9 or FIG. 1 in which the combustion gases are conducted upward by a right angle housing and separated from the fog jet nozzle. This modification may be specially adapted for operation with the embodiment of FIG. 8;

30 FIG. 9 shows a longitudinal cross section of the main unit of a fogger especially adapted for operation on "LPG" fuels;

FIG. 10 is a cross section on the line 10—10 of FIG. 9;

35 FIG. 11 is a cross section on the line 11—11 of FIG. 9;

FIG. 12 is a sectional view of the intake end of the fogger of FIG. 9 drawn to a larger scale;

40 FIG. 13 is a sectional view toward the outlet end of the fogger of FIG. 9, also drawn to a larger scale;

FIG. 14 is a sectional plan view of the burner wheel and scale shown taken on line 14—14 of FIG. 12;

FIG. 15 is a plan view of the control valve and calibrated cylinder of FIG. 12;

45 FIG. 16 is a cross sectional view of the air tube and jet nozzle mounted in the outlet cone of the fogger of FIG. 9 and drawn to a larger scale taken on line 16—16 of FIG. 17;

50 FIG. 17 is a view looking into the outlet end of the outlet cone shown in FIG. 16;

FIG. 18 is a cross sectional view taken on the line 18—18 of the jet nozzle of FIG. 17;

55 FIG. 19 is a diagrammatic view of the main fogger unit of FIG. 9 showing the liquid propane tank, the fog material tank and the water tank. The water pump driven from a vehicle on which the fogger may be mounted is also shown, together with the connections from the fuel, water and fog material sources to the fogger.

60 FIG. 20 shows diagrammatically an embodiment in which the main fogger unit of FIG. 9 is operated by utilizing the pressure from the liquid propane tank to pressurize the water supply to the fogger, the connections between the propane tank, the water tank and the fogger for this operation being shown;

65 FIG. 21 is a longitudinal cross section of an improved modification of the fogger shown in FIG. 9;

FIG. 22 is a cross section on line 22—22 of FIG. 21;

70 FIG. 23 is a diagrammatic showing of an improvement of the arrangement shown in FIG. 19 with additional functions and features and with the electrical connections shown for operating the pump motor and other elec-

trical features from the battery generator system of the automotive vehicle carrying the fogger;

FIG. 24 is a sectional view of an improved modification of the outlet and nozzle arrangement shown in FIGS. 5 and 17;

FIG. 25 is a view looking into the outlet end of the outlet cone shown in FIG. 24;

FIG. 26 is a view of the removable nozzle parts and scale trap removed from the nozzle body of FIG. 24, the section taken on line 26—26 of FIG. 25.

FIG. 21 illustrates an improved modification of the general type of fogger shown in FIG. 9. Inasmuch as there are many similar parts and similar functions in the device of FIG. 21, a somewhat less detailed description is considered adequate. Although the modification of FIG. 21 is most similar to the modification of FIG. 9, features of other modifications besides that of FIG. 9 may be combined with this modification of FIG. 21. The legends applied to various of the elements shown in FIG. 21 and arrows indicating direction of flow of fluids are explanatory thereof taken in connection with this specification. Similar legends and arrows have been applied to other figures in the drawings and for similar purposes.

Referring to FIGS. 1, 2 and 3, these figures show the complete fogger except for the liquid supply system. The complete fogger unit 10 is provided with an outer casing which may be divided into three parts. The burner housing 12 is removably connected to the body shell 14. The nose 16 is detachably connected to the other end of the body shell 14. The body shell is supported on rear legs 18 and front leg 20 which may be spotwelded or riveted to the body shell. The body shell is tubular and may be formed by rolling a sheet of aluminized steel into a tube and spot-welding the seam. The burner housing 12 may be a similarly formed tube having a solid disc 22 seamed into its rear end. An air inlet opening 24 may be provided in the bottom of the burner housing 22. A hinged cover 26 covers an access opening 28 at the top of the burner housing. The burner housing 12 may be attached to the body shell 14 by slipping it over the outside of the latter and fastening it with self-tapping screws. The nose 16 may be attached to the body shell 14 by a flange collar 30 which overhangs an outward flange at the rear end of the nose. The nose is provided with an opening to permit the passage therethrough of the jet nozzle and cooling tube 32. The nose 16 is formed from a sheet of aluminized steel and is of conical form with an open front end. The joint in the nose cone is not spot-welded but is held together by screws 34 so that the point can be opened to permit its assembly over the jet nozzle unit 32. A washer 36 is seamed or otherwise fastened into each end of the body shell 14. An inner shell 38 which may be a tube of stainless steel is carried by the washers 36 and projects slightly beyond the washer at the rear and considerably beyond at the front so as to form an additional support for the nose 16. Thus the interior of the fogger unit 10 forms a duct 40 having an inlet 24 and an outlet 42. Within this duct 40 a coil of steel tubing may be positioned which may constitute the main vaporizer 44. The vaporizer 44 may be carried by three angle strips 46. These may be of stainless steel and spaced around the interior of the inner lining 38. They may be fastened to the inner lining 38 solidly at one end and by means of a screw sliding in a slot at the other end to permit thermal expansion. The rear end of the vaporizer 44 has a straight portion 45 and passes out through the burner housing end plate 22. The front end of the vaporizer coil has a straight portion 47 and is threaded for the attachment of the jet nozzle unit 32. The jet nozzle unit 32 is secured to the nose by means of the stud bolt and nut 48 which passes through a hole in the top of the nose. The burner vaporizer 50 consists of a coil of steel tubing, one end of which is bent backward and passes out through a hole in the rear disc 22. The other end of

the burner vaporizer coil is straight and equipped with a thread which screws into the nozzle support 52. The burner nozzle 54 screws into a tapped hole in the support member 52. The nozzle 54 has a large internal bore reduced to a small nozzle orifice 55 at the end toward the burner vaporizer 50. The size of this nozzle orifice is such as to direct a jet of vaporized fuel at high velocity through the interior of the burner vaporizer 50. The nozzle orifice 55 must be of the proper size to generate the desired heat and to produce an injector action which induces a flow of air into the inlet opening 24 and also into the opening 28, thence through the duct 40 and out the duct outlet 42. The burner nozzle support 52 may be secured to the end plate 22 by means of a bolt and nut 56 attached to the nozzle support 52. The rearwardly bent straight portion of the burner vaporizer coil 50 may be secured to the burner housing 12 by means of a U-clamp 58 which may be attached to the burner housing by self-tapping screws. This U-clamp 58 together with the bolt and nut 56, securely supports the burner vaporizer 50. The burner vaporizer is surrounded by a vaporizer generating pan 62. This is preferably provided with a pad of glass cloth covering its bottom. This can be saturated with an appropriate fuel and ignited to generate the burner 30 when the device is first started i.e., to generate the fuel as a gas. If the burner fuel is used for generation, this may be supplied through the starting tube 64 which connects through the starting valve 66 with the burner control valve 68. The starting valve supplies fuel to the pan without filling the vaporizer coil 50. The burner control valve may be screwed onto a thread on the rearwardly extending end of the burner vaporizer 50. The valve 68 should meter the fuel accurately at specific angular settings. A heat insulation space 70 is provided between the lining 38 and the body shell 14. This may be filled with a heat insulation material such as Vermiculite. It also may be left empty. The diameter of the turns of the main vaporizer 44 may be larger at the rear of the vaporizer to provide additional space for the burner flame without direct contact with the vaporizer coils. The angle strips 46 may be cut down in height toward the rear end to accommodate these larger vaporizer turns. The fog oil supply tube 72 is connected to the lower end of the vaporizer jet nozzle 32. This is attached to the burner housing at the rear end by a support 74. Three connecting means are provided for the liquid supply to the fogger unit 10. These may be of the quick detachable type. The male member of a fitting of this type is shown in FIG. 4. One of these male members 76 may be connected to the fog oil supply tube 72. It will be noted that the male fitting 76 is provided with a plug pierced by a small orifice 78. The size of this orifice is such as to supply the desired amount of fog oil or formulation to the vaporizer jet nozzle 32. 60 Different sizes of orifice 78 may be employed to meet different conditions or an adjustable orifice or valve may be used if desired. A similar male fitting 76 is also screwed on to the straight rear portion 45 of the main vaporizer 44 where it projects through the rear disc 22. 65 In this case, the orifice 78 may be varied in a similar manner to control the liquid supply to the main vaporizer 44. The function of these orifices 78 will be more fully described. A male fitting 77, but without the plug and orifice 78, is attached to the fuel control valve 68, which valve performs the function of the orifice 78 in regard to the fuel supplied to the burner. Flexible liquid lines may be connected to the fittings 76 and 77 by means of a quick detachable female fitting 80 shown in FIG. 4(a). By means of the fitting 80, the liquid

lines may be quickly attached and detached to the fogger unit 10. The hinged cover 26 provides ready access for cleaning the burner nozzle 54 and may be opened for lighting the generator or for inspecting the fire. Additional air is also supplied under the right and left end of the cover 26. Reference is now made to FIGS. 5 and 6 which show the details of the vaporizer jet nozzle unit 32. The nozzle body 82 may be made of stainless steel and has an external thread on the rear and adapted to screw into the forward end 47 of the vaporizer coil 44. The other end carries an internal thread into which is screwed the expanding nozzle member 84. The nozzle orifice 86 is closely concentric with the tapered bore of the nozzle member 84 and is connected to the interior of the vaporizer 44 by an enlarged bore 88. At the bottom of the nozzle body 82 between the nozzle orifice 86 and the threaded portion of the nozzle member 84 is an opening 90. Into this opening, a stainless steel tube 92 may be silver-soldered or welded. To the other end of this tube 92, an elbow 94 may be silver-soldered with a suitable screw connection for attachment of the tube 72. The front end of the nozzle member 84 carries serrations 96. The lower front surface of the body 82 is also provided with a slot 98. A wire spring 100 is urged into this slot 98 and the serrations 96 to lock the nozzle member 84 against angular movement. The liquid supply tube 92 communicates with an annular space 102 which surrounds the rear end of the nozzle member 84. The member 84 is screwed in to a point which leaves an annular aperture 104 of the proper width. Through this annular aperture which surrounds the vapor jet issuing from the nozzle aperture 86 the fog producing or treatment material is sucked in to the vapor jet by the venturi action of the jet. The annular aperture 104 should be of such width as to provide adequate vacuum and to avoid plugging. It will be seen that this construction provides an uninterrupted annular passage 104 so that an uninterrupted ring of the liquid to be atomized is exposed to the periphery of the jet. This tends to increase the quantity that can be finely atomized. The expanding bore of the member 84 extends for a short distance forwardly from the annular orifice 104. If the bore of the member 84 is made the proper amount larger than the bore 86 a fairly high vacuum can be obtained. This facilitates atomization and raising of the liquid to be atomized a considerable distance if desired, especially when adequate pressure is maintained in the vaporizer 44. The annular grooves 106 are for the purpose of thermally isolating the liquid in the space 102 from the hot rear portion of the nozzle body. It is desirable to keep the liquid to be vaporized reasonably cool to prevent carbonization of insecticide which might plug the nozzle and also to prevent the overheating of any insecticide or treatment material contained in the liquid to be vaporized. This purpose is also served by the jet nozzle cooling tube 108 which surrounds the forward portion of the body 82 and also the tube 92. The vapor jet issuing from the nozzle member 84 passes through an aperture 110 in the tube 108. This jet induces a flow of cool outside air into the bottom opening 112 which passes over the tube 92 and the body 82, cooling them and shielding them from the hot combustion of gases issuing from the duct outlet 42. Further, this cool air passing out the orifice 110 surrounds the jet of vapor and treatment material as it passes out the outlet 42, thus tending to shield the fog jet from the hot gas flow which surrounds it. This arrangement has been found to be advantageous when certain fogging materials are used and it permits higher gas temperatures and tends to prevent carbonization of nozzle parts. A plug 114 may be pressed into the top of the cooling tube 108. This plug may carry a bolt and nut combination 48 which connects the jet nozzle

unit 32 to the nose 16. A nut 116 clamps the tube 108 to the nozzle body 82. The tube 108 is slotted on its forward side as indicated at 118 so that the assembly of the nozzle body 82, tube 92 and elbow 94 can be passed to the interior of the tube. A curved plate 120 is then attached to the front of the tube 108 to cover the slot. The plate 120 is held by the screw 122 and the inturned lip 124. The screw 126 holds one end of the spring 100 to the plate 120 which plate has a hole registering with the hole 110.

Referring now to FIG. 7, the fogger unit 10 previously described may be mounted on an automotive vehicle such, for instance, as a jeep or truck indicated by the number 128. Two L-shaped brackets 130 and 132 may be attached to the vehicle and the feet of the fogger unit 18 and 20 may be bolted to the horizontal member of these brackets. Due to the relative lightness of the fogger unit 10, this mounting means is adequately strong. The outlet end or front of the unit 10 may be directed rearwardly and outwardly with relation to the vehicle so that the jet is projected in such a way as not to eddy behind the vehicle when moving. The direction of the jet can of course be altered by varying the position of the unit 10 relative to the vehicle. For the embodiment of the invention now being described, three separate liquid sources may be employed. Two of these liquids may be supplied under pressure, one to the burner connection 76 and one to the vaporizer connection 45. As shown in FIG. 7, water or other liquid may be supplied under pressure from the pump 134 which may be a gear pump or other suitable pump driven by means of a belt 136 from the engine power take off 138 associated with the vehicle 128 and supplied with power from its power source. The water is supplied from the tank 139 to the intake of the pump 134 through the pipe 140 and shut off valve 142. The water under pressure is delivered to the vaporizer connection 45 through the pipe 144 and flexible connection 146. The pressure of the water supply may be indicated by a gauge 148. The water pressure may be held near to the desired pressure with a spring-loaded liquid by-pass valve 150 which may be integral with the pump 134. This by-pass valve 150 has a ball valve 152 held against its seat by a compression spring, the force of which is varied by the adjustment screw 154. The spring side of this valve is connected to the pump intake and the opposite side of the valve to the pump outlet. Thus, when the outlet pressure exceeds the spring-loading of the valve, water is by-passed back to the inlet. By incorporating the by-pass valve 150 with the pump 134 and having passages of short length and large area, closer pressure regulation may be obtained. The water supply under pressure in the pipe 144 is also communicated to the fuel tank 156 through the pipe 158 and valve 160. A baffle 161 is provided where the water enters the tank 156 to prevent it from squirting upward. The fuel which may be for instance No. 1 furnace oil or kerosene is shown at 162 occupying the upper portion of the tank 156. The tank is equipped with a sight level gauge 166. Pressure is applied to the fuel 162 in the tank 156 by water 164 pumped into the bottom of the tank by the pump 134 through the pipe 158. As the fuel 162 is lighter than the water 164, it floats on the water and may be displaced into the flexible connection 168 which connects to the fitting 77 carried by the fuel valve 68. However, it may be desirable to supply fuel to the burner at a somewhat lower pressure than that generated by the pump in the water line 158. Thus a pressure regulating valve 170 may be employed to regulate and reduce the pressure in the line 168 below that in the line 158 and the tank 156. A gauge 172 may be employed on the outlet side of the reducing valve 170 showing this lower pressure. The regulating valve could also be installed in the line 158 and the line 168 connected directly to the tank if desired. The drain valve 174 may be

opened to drain the water out of the tank 156 after it has been filled with water and all of the fuel displaced. After the tank is drained, it can then be refilled with oil through the pressure seal filler cap 176. The level of the fuel can be seen at all times in the sight gauge 166. After the water is drained, the valve 174 is closed before the tank is refilled with fuel. The tank 178 contains the supply of fog oil, insecticide or any formulation material 180 which may be employed. The tank 178 may be filled through an appropriate filler cap. A stand pipe 182 extends to the bottom of the tank and is connected to a valve 184 for shut off and/or adjustment of flow. This valve is connected to a strainer 186 which supplies the material 180 through the flexible connection 188 to the connection 76 and the pipe 72 which in turn connects to the pipe 92 attached to the jet nozzle body 82. It will be understood that tank 178 must be so positioned that the suction generated in the jet nozzle orifice 102 is sufficient to raise the desired amount of the material 180. The tank may be above or below the level of the jet nozzle but must not be too far below and is generally located at or somewhere near the same level. One advantage of the lower tank is that no fog material can siphon out when operation is discontinued. The water tank 139 must also be positioned so that the pump 134 can raise the water and it may be preferable to position the water tank 139 with its bottom somewhat above the pump intake, especially when a low lift pump is employed. All three of the tanks 139, 156 and 178 may be mounted on the vehicle 128 which carries the fogger 10. If little or no portability is required the fogger may be mounted on a stand adapted to rest on the ground and the water under pressure may be supplied if desired from a municipal water faucet instead of from the tank 139 and the pump 134. If the municipal water pressure is too high or not sufficiently constant, a pressure regulator similar to the pressure regulator 170 may be connected between the municipal water faucet and the pipe 144 which may be broken at any convenient point to substitute the municipal water supply for the pump 134. FIG. 8 shows an embodiment of the invention quite similar to that of FIG. 7 except that a liquid such as No. 1 or No. 2 furnace oil is supplied to and vaporized in the vaporizer 44. This material may also be used for burner fuel, thus eliminating the necessity of a separate fuel tank. The common fuel and fog oil tank is given the number 139'. The fuel and fog oil from the tank 139' is supplied through the pipe 140' to the pump 134' and through the flexible connection 146' to the rear end of the vaporizer 45'. The fuel is supplied from the pump 134' through the reducing valve 170', the flexible line 168' to the burner fuel supply fitting 177'. The formulation material is supplied to the jet nozzle supply pipe 72' from the tank 178' through the valve 184', strainer 186' and flexible connection 188' in the same manner as described in the embodiment of FIG. 7. It may be mentioned that the orifice in the detachable connection 76 of FIG. 4 in the vaporizer connection 45' and the formulation connection 76' will most likely be of a different size than those employed in the embodiment of FIG. 7. A larger volume of fog can be produced when a fog forming material such as oil is used in the vaporizer instead of water. Also the weight of the water and tank is avoided.

Referring to FIGS. 9, 10, 11, 12 and 13, these figures show a further embodiment of the invention especially adapted for operation on fuels of the character of propane, butane, etc., known commercially as "liquid petroleum gas" or "LPG."

FIG. 9 shows the fogger unit 300 for operation preferably, but not necessarily, on liquid propane. This unit is supplied with water, gas and fog oil as shown in other figures and later more fully described.

As shown in FIGS. 9, 10, 11, 12 and 13, the outer

75 casing consists of an elongated cylinder carrying an outlet cone at one end and a burner plate at the other. The burner may be supported on the burner plate 302 which is connected to the body shell 304 by spacing members 306. The annular space between the burner plate 302 and the body shell 304 constitutes the air intake through which the flow of air is induced by the injector effect of the burner. The outlet cone or nose 308 is detachably clamped to the flanged outlet end of the body shell 304 by means of a bead at the large end of the nose 308 which is drawn up in clamping relation to the outturned flange by the screw clamp 310. The body shell is supported on rear legs 312 and front leg 314. The body shell 304 may be formed of a single sheet of aluminized or other suitable steel rolled into a tube with the ends welded or otherwise secured together. The nose 308 may be formed into conical shape from a flat sheet and the overlapping ends detachably secured together with screws to permit it to be assembled around the jet nozzle and air tube assembly 342 later to be described. An inner shell 316 may be a tube of stainless steel rolled up with the abutting or overlapping ends secured together, for instance by welding. Within the duct formed by the inner shell 316, a coil of steel tubing is positioned forming the vaporizer 318. Combustion gases from the burner pass mainly through the interior of the vaporizer coil. Thus, the vaporizer 318 shields the inner shell 316 and the inner shell shields the outer shell 304 from the heat of the burner. This reduces heat losses as well as reducing the temperature of the outer shell. The vaporizer is supported by angle fins 320 which may for instance be four in number. These fins are secured to the inner shell 316 near the outlet end by bolts 322 passing through the bent over portion of the fins 320 and through the inner shell 316 and clamped by a nut. The bottom one of these bolts 322 screws into a spacer nut 324 which together with the other bolts 322 space the inner shell 316 from the outer shell 304 near the outlet end. The spacer 324 is in turn fastened to the outer shell 304 by the bolt 326. This is the only point of fixed attachment between the outer shell 304 and the inner shell 316. Near the intake end, the inner shell 316 is spaced from the outer shell 304 by the bent over ends 328 of the fins 320. These ends are positioned by slots 330 in the intake end of the inner shell. The ends 328 are in turn prevented from inward displacement by the pieces 332 which are wider than the slots and are welded to the ends 328. The ends 328 are free to move axially in the slots 330 and also with relation to the outer shell 304 so that the parts can accommodate themselves to the expansion and contraction resulting from heating and cooling. The single attachment between the inner and outer shell by the bolt 326 also permits free expansion and contraction of the members, especially in their direction of greatest length. Supporting the inner shell on the four ends 328 also makes for easy fitting on assembly. The intake end 334 of the vaporizer 318 passes out through a hole in the burner plate 302. The outlet end of the vaporizer has a straight portion 336 which is threaded for attachment of the steam strainer 338 which encloses the strainer screen 340. The jet nozzle unit 342 which will be later more fully described is attached in turn to the outlet end of the steam strainer 338. The jet nozzle unit 342 passes through suitable holes in the top and the bottom of the nose 308 and is attached thereto by means of the drip trough 344 which is in turn fastened to the unit 342 and to the nose 308, for instance by means of screws. The drip trough prevents liquid drip from running into the body where it might cause combustion. The burner tube 346 is secured to the end plate 348 which carries a mixing tube 350 which passes through the plate 348 and is threaded at the end. The mixing nozzle 352 screws on to the threaded end of the mixing tube 350.

and clamps the burner unit as a whole to the burner plate 302. The other end of the mixing nozzle 352 is threaded for attachment of the burner valve 354. The burner valve unit 354 is provided with a strainer housing 356 containing a fuel strainer, not shown. It is also provided with a boss into which the pilot light valve 358 is screwed. The pilot light 360 is supplied with gas from the gas valve unit 354 by means of the connecting tube 362. Air is supplied to the pilot light through the orifice 364 which, together with the small bore gas orifice (not shown), constitutes a Bunsen-type burner. This is directed upwardly toward the burner tube 346 and made less subject to blow out by means of the U-shaped strip 366 which covers the end of pilot light 360 in closely spaced relation. In one leg of the U member 366, a hole is provided which fits tightly over the pilot light 360 and the two parts may also be welded together or otherwise fastened. The pilot light 360 is secured to the burner plate 302 by means of a bracket 368. The gas inlet end of the burner valve 354 is provided with a male element of a quick disconnect fitting similar to that shown in FIG. 4. Fuel is supplied to this through the female portion of a quick disconnect fitting similar to that shown in FIG. 4a which in turn may be connected to a suitable pressure hose which in turn connects to the source of propane or other fuel as will be later more fully described. The burner valve 354 includes a needle-type of valve, not shown, which is raised more or less off its seat by rotation of the burner valve wheel 370. The wheel is connected by the valve shaft to the burner scale 372 shown in plan view in FIG. 14. The figures on the scale 372 are read against the burner indicator 374 and by setting the scale so that the proper number comes opposite the indicator, a pre-determined burner setting to supply the desired amount of heat may be made. After the fuel passes through the burner valve, it is discharged in a jet through the nozzle orifice 376. Primary air is induced by this jet through the air inlets 378, and mixing occurs in the mixing tube 350. Burning and mixing with secondary air occurs in and adjacent the outer end of the burner tube 346, which also acts as a flame holder. The straight inlet end 334 of the vaporizer 318 passes out through a hole in the burner plate 302. This inlet end is threaded for a T fitting 380. In the upper opening of this T is mounted a steam pressure gauge 382 which indicates the steam pressure in the vaporizer 318. Into the third opening of the T 380 may be screwed the male member of a quick detachable fitting 384. This fitting is provided at its inlet end with a small orifice 386. This orifice is similar to the orifice 78 shown to a larger scale in FIG. 4. The fitting 384 is also similar except that it has a male thread on the end which screws into the T 380. The end of the pressure hose 388 through which water is supplied to the vaporizer is attached to a quick connector fitting shown to a larger scale in FIG. 4a. This fitting 80 can be quickly connected to or disconnected from the fitting 384. The orifice 386 is also proportioned so as to permit the passage of the proper amount of water to maintain the desired pressure in the vaporizer as indicated by the gauge 382. This pressure may be for instance forty or fifty p.s.i., but of course a different pressure may be employed if desired. The supply of water under pressure to the hose 388 will be later more fully described. Fog oil or any desired formulation, with or without insecticide, is supplied through the hose 390 which connects to a similar quick connector fitting 392. This is detachably connected to the fitting 394 to supply the formulation to the formulation control valve 396. This valve has a manually operable cylindrical scale 398 which is read against the arrow 400. The valve 396 may be a needle valve and when the cylinder 398 is turned to the right, it is fully

closed and reads zero. When it is turned to the left, the needle valve is screwed up off the seat and permits the flow of formulation depending on the degree to which the valve is opened. The desired flow of formulation is secured by opening the valve to a number corresponding to the desired rate of flow. A dryer fog is produced by a smaller opening of the valve and a wetter fog when the valve is more widely opened. With maximum rate of flow large bore lines and fittings should be provided. The valve 396 is connected to a T member 402 which also receives the threaded end of the fog oil or formulation line 404. Into the third opening of the T 402 is screwed a vacuum gauge 406 which indicates the vacuum created by the flow of steam from the jet nozzle later to be described. This vacuum causes the fog oil to flow through the valve 396 and the pipe 404 to the jet nozzle. It is desirable to seal the annular passage between the outer or body shell 304 and the inner shell 316. This is done by means of the washers 408 between which is interposed a refractory sealing material 410 which may be, for instance, asbestos wicking. The washer 408 toward the inlet end is held in axial position by the bolts 322 and the washer toward the outlet end is held by the screws 412. This arrangement and also the way in which the outlet cone 308 is clamped to the body shell 304 is best shown in FIG. 13.

Referring now to FIG. 16, the outlet cone 308 carries the air tube and jet nozzle assembly generally designated as 342. The assembly 342 is secured to the tail cone 308 by means of the fitting which supports the drip trough 344 which in turn is secured to the air tube assembly by the screws 416.

Referring now to FIGS. 16, 17 and 18, the fog oil line 404 connects by means for instance of a compression fitting, not shown, to the fog oil tube 418. This tube is connected by a special fitting 420 to the riser tube 422. The fitting 420 is firmly held by a slot in the bottom of the air tube 424, the edges of which engage slots in the fitting 420. The upper end of the riser tube 422 is inserted into a hole in the jet nozzle body 426. This tube 422 may be silver soldered into the nozzle body and also into the fitting 420. The steam fitting 428 is screwed into the small threaded bore in the nozzle body 426 and clamps the nozzle body to the wall of the air tube 424. The intake end of the steam fitting 428 screws into the strainer housing 338. The multiple nozzle member 430 fits into the nozzle body 426 and forms a tight seal between the steam passage 432 and the fog oil passage 434. The annular passage 434 communicates with the interior of the tube 422. The nozzle outlet member 436 carries an external thread which engages a thread at the outlet end of the nozzle body 426 locking the multiple nozzle unit 430 in place. Between the members 430 and 436 is a flat conical space 438 which extends outwardly beyond the multiple steam nozzles 440 and the multiple fog oil nozzles 442. The space 438 connects to the annular fog oil passage 434 by means of a straight slot 444 in the multiple nozzle member 430. Thus a steam jet issuing from the multiple steam nozzles 440 and passing through the larger diameter fog oil nozzle holes 442 is completely surrounded by fog oil which fills the thin conical space 438. The diameters of the holes 440 are about .086 inch and the diameters of the holes 442 are about .120 inch. Thus the holes 440 are near 70% of the diameters of the holes 442. This relation has been found to give good operation. The high velocity steam jet issuing from the nozzles 440 expands, and entrains and projects outwardly any fluid in the space 438, thus creating a vacuum and sucking up the fog oil from the tube 418 through the tube 422 through the annular passage 434 through the slot 444 into the space 438 and out the multiple fog oil nozzles 442. The steam nozzle 440 and the fog oil nozzles

442 diverge outwardly from the central axis at an angle of about 15°. If this angle is too large low axial velocity and fog oil ignition may result. If the angle is too small mixing with the hot gases is reduced and the fog may be wetter. Attention is called to the fact that the multiple fog oil nozzles 442 must be located coaxially with the multiple steam nozzles 440. This relation is insured by inserting one or more rods, the small diameter of which fits the holes 440 and the large diameter of which fits the holes 442. The member 436 is screwed up tight with these rods in place. In fact, the torsion may be applied by means of these rods. After the retaining member 436 is tightened up, the rods may be removed and the two sets of multiple bores will then be in proper alignment. Attention is called to the ejector effect of the steam jets issuing from the fog oil nozzles 442. This ejects air from the inside of the air tube 424 which causes a flow of air into the top and the bottom of the air tube and out through the air tube nozzle orifice 446. This flow of air prevents the hot combustion gases issuing from the outlet cone 308 from overheating the fog oil in the tube 422 and the nozzle boy 426. It is especially desirable to avoid overheating of the fog oil when it carries a formulation of, for instance, insecticidal material which may be decomposed and rendered relatively ineffective by excessive heat. The cool air ejected out of the orifice 446 also reduces the effect of the hot combustion gases on the atomized or vaporized formulation issuing from the nozzles 442, the jets from these nozzles are surrounded by the hot gases issuing from the outlet cone 308, and the outward flow of the combustion gases are augmented by a second ejector effect of jets. By employing a multiple nozzle having a total area such as to produce the proper flow of steam, a longer contact line is obtained between the periphery of the steam jets and the fog oil in the space 438. This is beneficial to fine atomization. The multiple nozzle is also beneficial from the point of view of better augmentation of the flow of hot gases and reduction of aerosol particle sizes as the result of better mixing with the hot gases.

Referring now to FIG. 19, the supply of formulation or fog material to the fog oil hose 388 will now be described. The fog oil may be contained in a fog material tank 448 having a vented filler cap 450. This tank is preferably not too high from bottom to top so as to reduce the difference in gravity head from when the tank is full to when the tank is nearly empty. The tank may be provided with a pipe 452 running to near the bottom where it may carry a strainer 454. A shut off valve 456 may be provided by means of which the flow of fog material may be cut off to stop fog generation without altering the setting of the valve control valve 396. The valve 456 may be connected to the control valve 396 by means of the hose 390 and the quick disconnect fittings 392 and 394. The control valve 396 in turn connects to the fog oil pipe 404 through the T fitting 402 carrying the gauge 406 which shows the reduction of pressure in the fog oil line.

The fuel, which may be for instance liquid propane, may be contained in a pressure tank 458. This is provided with a shut off valve 460. This valve is connected by a pipe 462 to a pressure reducing and regulating valve 464 which, by means of a properly arranged spring-balanced diaphragm, maintains a desired pressure on the outlet side to which may be connected a fuel pressure gauge 466. This may be connected by a flexible pressure tube 468 and quick disconnect fittings 470 and 472 to the burner valve 354 from which the gas may be supplied to the nozzle orifice 376 as previously described. If liquid propane is used for fuel and if the tank 458 is sufficiently large relative to the amount of fuel being used, sufficient vaporization will occur within the tank except at quite low atmospheric temperature. If fuels of higher boiling point are employed or use at lower

temperatures intended, some form of vaporizer may be employed such, for instance, as that shown in FIG. 1 or some other type. Also by application of extra heat to the fuel tank operation may be made satisfactory at lower temperature.

5 Water or other liquid may be supplied to the inlet end 334 of the vaporizer 318 from a water tank 474. This water tank may be considerably smaller if desired than the fog material tank 448 as much less water may be used than fog oil during a given period of fogging. 10 The water tank is provided with a vented filler cap 476. In this embodiment, the water tank may be made of light material as it is not subject to pressure. The water tank 474 is connected to a water pump 478 through 15 a pipe 480 which may be equipped with a shut off valve 482. The pump 478 may be for instance a small gear pump and may be driven from the engine 485 in the vehicle carrying the fogger by means of a belt 484. Other types of pump may also be employed. The pump 20 478 may be equipped with a spring-loaded by-pass valve 486 which is interposed between the inlet and outlet and is adjusted to by-pass water from the outlet to the inlet through this spring-loaded valve when the pressure exceeds a given value occasioned for instance by the 25 speeding up of the pump drive by acceleration of the vehicle motor. The outlet of the pump 478 may be connected to a water pressure regulator 488 by a pipe 490 if closer pressure regulation is desired. The outlet side of the pressure regulator 488 carries a gauge 492 and a flexible pressure hose 388. The water supply 30 under the pressure determined by the setting of the pressure regulator 488 is thus maintained on the water supply side of the water orifice 386 in the fitting 384. Thus the water gauge 492 shows the water pressure on the inlet side of the orifice 386 while the steam gauge 382 shows the water or steam pressure on the vaporizer side of the orifice 386. The size of this orifice and the pressure difference on opposite sides thereof determine the flow 35 of water into the vaporizer.

40 By varying the size of the orifice 386 and by varying the water pressure, the fogging rate, the character and micron size of the fog can be influenced. Also, the amount of water or other liquid consumed with relation to the amount of formulation put out in the same period of time.

45 Referring now to FIG. 20, there is shown an embodiment in which the fogger unit 300 and fog material tank 448 may be the same and in which the same parts are designated by the same numbers as in FIG. 19, but other 50 parts are given higher numbers. However, water or other liquid under pressure is supplied to the end 334 of the vaporizer 318 by the pressure of the vaporized propane supplied from the propane tank to the burner. The propane tank 494 is provided with a shut off valve 496, similar to that described in FIG. 19. A pressure regulator 498 is connected to the valve 496 by pipe 500. The pressure regulator 498 may be connected to a T fitting 502 by a connection 504 which is equipped with a pressure gauge 506. One opening of the T fitting 502 is connected 55 to the flexible pressure hose 468 to supply fuel to the burner valve 354. The water tank 508 is constructed to withstand considerable pressure. It is provided with a pressure release or safety valve 510 which is set to release the pressure at a value considerably below that which the tank 508 can safely hold. The tank 508 may be filled with water or other liquid to be supplied to the vaporizer by means of a tightly sealing filler cap 512. A connection 514 from the tank 508 carries a shut-off valve 516. This is in turn connected to the T fitting 502 by a 60 connecting pipe 518. Thus the pressure of the vaporized propane, or other low boiling point fuel, in the tank 494 may pass through the open valve 496, the connection 500 to the pressure regulator 498 where its pressure is reduced to for instance 50 p.s.i. The gas then passes through the 65 connection 504 to the T fitting 502, the pressure being indicated by the gauge 506.

cated by the gauge 506. This pressurized gas then passes through connection 518, valve 516 and connection 514 to the tank 508 where the pressure of the gas is supplied to the water or other suitable liquid in the tank 508. At the bottom of the tank 508 a shut-off valve is provided communicating with the water in the tank. When this valve is open, water is supplied through the pressure hose 388, one end of which may be connected to the valve 520. The water in the hose 388 is supplied under the pressure indicated by the gauge 506 to the water inlet side of the orifice 386 through which it is fed to the inlet end 334 of the vaporizer 318. It will be seen that with this arrangement the same pressure will be supplied to the burner valve 354 that is supplied to the water tank 508 and to the inlet side of the water orifice 386. Both the water pressure to the vaporizer and the gas pressure to the burner may be controlled simultaneously by the pressure regulator 498. It will be seen that this constitutes a simple and effective way of supplying liquid under pressure to the vaporizer without the use of a pump. However, a heavier water tank 508 is required when the tank itself is subject to the pressure instead of the pressure appearing only at the outlet side of a pump as shown in FIG. 19. When liquid propane is employed in tank 494 and water in tank 508, there is a certain amount of absorption of the gas by the water if they are allowed to stand for extended periods of time in contact with each other under pressures substantially above atmosphere. When sufficient gas is absorbed by the water, there may be a tendency for the pressure in the vaporizer 318 to show fairly large and more or less periodic fluctuations. For this reason, it is desirable to release the gas pressure on the water tank and/or drain the water from the tank during extended periods of non-use. No additional loss of gas will result if the water tank 508 is completely filled with water through the filler 512 before operation is resumed. The gas used for pressurizing the water is only equal to the volume of water displaced at the water supply pressure and appears to be substantially less than 10% of the gas used by the burner in certain applications. This method of pressurizing the water supply makes the operation of the fogger independent of any power source such, for instance, as the engine 485. The tank 508 may be provided with a water gauge 524 by which the remaining supply of water can be determined at any time. The valve 520 may also be provided with a water drain cock 526 by which water saturated with gas may be drained off. It will be understood that gas other than propane may be employed and liquid other than water may be supplied to the vaporizer 318 by pressurizing the liquid supply with pressurized gas. However, the gas and the liquid selected must be such that the gas will not be too readily soluble in the liquid. This pumpless system may be of special advantage for certain applications, for instance in a small manually portable unit, or where power to drive a pump presents difficulties.

The operation of the embodiment shown in FIGS. 9, 10, 11, 12, 13, 14, 15, 16, 17, 18 and 19 will first be described. As there is much similarity in the operation of all embodiments, it will not be necessary to describe each in complete detail. After the operation of the embodiment covered by the above-mentioned figures has been explained, the differences of operation of the other embodiments from this one will be brought out.

The fogger unit 300 may be mounted on some automotive vehicle, for instance a "Jeep." The fog material tank 448, the propane or "LPG" tank 458 and the water tank 474 may be mounted in the body of the "Jeep." The water pump 478 may be driven from the "Jeep" engine 485. Other means of driving the pump 478 which requires only relatively small power may alternatively be provided. It is preferable to mount the fog material tank 448 so that its top is slightly below the horizontal center line of the fogger unit 300 so that fog material or fog oil will not siphon out when the fogger is not oper-

ating. The water tank 474 may be mounted slightly above the pump 478 so as to avoid raising the water to the pump intake. To start the fogger in operation, the valve 460 on the propane tank 458 is first opened. The pressure regulator 464 is then adjusted to supply the desired pressure to the burner. The pilot light valve 358 is then opened and the pilot light 360 lit by applying a flame to the lighting hole 361. At this point the "Jeep" engine 485 should be in operation and driving the pump 478. The water valve 482 should be open. Water will then flow from the pressure hose 388 through the orifice 386 into the straight intake end of the vaporizer 334 through the vaporizer 318 through the straight outlet end of the vaporizer 336 into the steam strainer 338 into the nozzle body 426 and through the multiple steam passages 440 and out the openings 442. After the presence of water in the vaporizer 318 is assured, the burner valve wheel 370 is turned so that the burner scale 372 is open for instance to 8. Gas will then flow through the partially opened burner valve and issue as a jet from the mixing nozzle 376. The jet induces a flow of air into the mixing jet air openings 378 and through the mixing tube 350. This mixture of air and gas then issues from the open end of the burner shell 346 and is ignited by the flame of the pilot light 369. The gas pressure regulator valve 464 may then be adjusted so that the fuel gauge 466 reads for instance 30 p.s.i. The water pressure regulator 488 may then be adjusted so that the water gauge 492 is for instance 50 p.s.i. A mixture of water and steam will then issue from the openings 442. This will very shortly become dry superheated steam, if the burner valve adjustment has been properly made. The pressure in the vaporizer 318 will then approach a steady pressure for instance 40 p.s.i. as shown by the steam gauge 382. If the setting of the burner valve is too low, the steam issuing from the openings 442 will be wet and clearly visible to the eye. The burner setting can then be slightly increased until the steam is dry and invisible. If the burner valve setting is too high, the steam gauge 382 will be unsteady and may show fairly large fluctuations. This can be corrected by reducing the gas supply to the burner by setting the burner dial to a lower number. When the proper setting of the burner dial is attained, the steam pressure in the vaporizer as indicated by the gauge 382 will be relatively constant. During the starting period, the fog material shut-off valve 456 and/or the fog material control valve 396 should be closed so that no fog material is delivered to the conical fog oil space 438. Under these circumstances, the vacuum created by the jets from the multiple steam nozzles 440 passing out through the fog oil openings 442 will be transmitted from the space 438 through the slot 444 through the annular passage 434 through the tube 422 through the fitting 420 and the tubes 418 and 404 to the T member 402 and will be indicated by the vacuum gauge 406. This might show for instance a vacuum of 20 inches. However, after the steam pressure in the vaporizer has been stabilized, the fog oil scale 398 may be opened for instance to eight which may give a moderate fogging rate. The shut-off valve 456 may then be opened and fog oil or fog formulation will be raised from the tank 448 through the strainer 454 through the tube 452 and valve 456 to flexible tube 390, quick disconnect fittings 392 and 394 through control valve 396 into T member 402 and thence to the fog oil space 438 by the path described for the communication between this space and the vacuum gauge. The fog oil in the space 438 surrounds each of the steam jets issuing from the multiple jet nozzles 440 and a mixture of superheated steam and fog oil vaporized and atomized to form an aerosol issues from the multiple fog oil openings 442. Cool air from the interior of the air tube 424 is also picked up by the multiple jets and passes out the opening 446 therewith. These jets in turn mix with and augment the flow of the hot gases issuing from the outlet cone 308. This flow of steam,

fog oil and hot gases forms a high velocity jet which is projected axially for a considerable distance behind the outlet end of the nose 303. If it is desired to have the fog very dry, the scale 398 of the control valve 396 may be set to a lower number. The rate at which formulation is delivered in the form of fog will then be somewhat lower. On the other hand, if it is desired to increase the rate of formulation delivery, the scale 398 is set to a higher number and may even be opened to a second or third turn depending on the construction of the valve. When the control valve 396 is opened, a large amount of formulation may be delivered per unit of time, such for instance as 30 gallons per hour. For highest delivery the bore of the whole fog oil line must be large and free of restriction. Also the fog oil lift should be minimized. Under these conditions, a wetter fog containing more large sized droplets will be delivered. A finer particle size and a dryer fog can be provided without reducing the rate of formulation delivery by setting the burner valve to a higher number to supply more heat to the vaporizer and to the hot gases issuing from the nose 308. A larger and hotter supply of steam may also be provided. However, if the burner is set too high, without increase in the water supply, fluctuations in the steam pressure may be encountered. Also, an excessively high setting of the burner valve together with a high setting of the formulation control valve 396 might cause ignition of the fog if the formulation is highly inflammable. If a fog oil such as No. 2 furnace oil is employed, more than thirty gallons per hour may be fogged with no tendency whatever to ignition of the fog oil. In fact, if the fog close to the nose 308 is ignited from the outside with a torch, it will immediately put itself out. If it is desired to briefly discontinue fogging, the shut-off valve 456 may be closed, thus interrupting the delivery of fog material. During this time, the burner will still continue to operate and steam will still issue from the multiple jet nozzles. Fogging can then be resumed at any time by merely again opening the valve 456. It is desirable to place this valve within reach of an operator on the "Jeep" so that the fog can be turned on and off quickly. Remote control of the valve 456 by means for instance of a flexible shaft may alternatively be provided. If it is desired to discontinue operation for a longer time, the burner valve 354 and the water valve 482 may both be closed. The pilot light 360 may continue to burn during the shut-down so that restarting is effected by simply opening the burner valve 354 and the water shut-off valve 382, the burner being again relit from the pilot light. Due to the fact that the fog material supply in the tank 448 and the water supply in the tank 474 are not subjected to pressure, the filler caps 450 and 476 respectively can at any time be removed to determine the amount of liquid still remaining in the tanks. The supply of liquid propane in the tank 458 may be determined for instance by keeping a record of the time that the burner operates. Tanks of propane gas suitable for this purpose are available commercially and when empty may be exchanged for full tanks. Suitable equipment is also available for refilling the same tank from a private supply of liquid propane. Under the latter circumstances, any unused gas remaining in the tank reduces the amount required to refilling and there is no waste of the quantity remaining in the tank after the pressure falls below that required for operation.

The operation of the embodiment shown in FIG. 20 is similar to that described in connection with FIG. 19 and previous figures, except that no power drive or pump for the liquid supplied to the vaporizer 318 is required. To start, the valve 496 on the propane tank is opened and the pilot light 360 is lit as previously described. The valves 516 and 520 are then opened to supply water from the tank 508 through the valve 520 and the hose 588 through the vaporizer 318. The pressure regulator 498 is then adjusted until the gauge 506 reads the desired pressure, for instance 50 p.s.i. The burner valve 354 is

then opened and the burner adjusted to provide the proper steady steam pressure in the vaporizer as shown by the steam gauge 382 as has been previously described. The gauge 506 may show a pressure of for instance 50 p.s.i. which will be, in this embodiment, the pressure applied to the burner and also to the water supply in the tank 508. The operation of this embodiment is otherwise substantially the same as that described in connection with FIG. 19. To terminate operation, the valve 496 may be closed. The valve 516 and the valve 520 may then also be closed to completely shut down the fogger. If operation is resumed again shortly, for instance within an hour or so, and if the water supply as indicated by the water gauge 524 has not been exhausted, operation of the fogger can be resumed by following the same procedure as described when first starting. However, if operation is not to be resumed until the next day or a longer period, it is desirable to release the gas in the tank 508 to prevent too much absorption of gas by the water. This pressure may be released for instance by partially opening the filler cap 512 until the pressure has fallen to atmosphere. This should be done out of doors where released gas is immediately dissipated. The tank 508 may then be completely filled with water and the filler cap replaced. It is then ready for a new start. This procedure prevents the absorption of the gas in the tank 508 by the water which may interfere with the best operation if gas under pressure stands for long periods in contact with the water. If the water in the tank 508 has already absorbed too much gas, the water may be drained from the tank by means of the drain cock 526 and the tank completely refilled with fresh water. No inflammable mixtures can be formed within the tank 508 as long as it is kept full of either propane gas or water. Propane gas mixtures with air in order to be inflammable must contain nearly 90% of air. This condition could never be present with proper operation and, even if it were, a flame or spark would still have to be applied to the interior of the tank. Like a gasoline tank, a propane tank should not stand with its cover removed in the presence of fire. The special features of the operation of the embodiment of FIGS. 1, 2, 3, 5, 6 and 7 will now be described. The fogger shown in these figures is similar to the embodiment shown in FIG. 9 except that the fogger in FIG. 1 is adapted to operate with fuel such as kerosene or furnace oil which requires a source of heat other than atmospheric temperature for satisfactory vaporization.

It may be mentioned that when "LPG" consisting mainly of butane or other higher boiling point materials is used, a vaporizer heated by other means besides atmospheric temperature may be required. This may even be true of propane at low atmospheric temperatures when a large amount of fuel is being used from a relatively small fuel tank. It should be noted that the kind of vaporization employed depends on the particular fuel used and the prevailing atmospheric temperature. When the heat of the burner flame is used to vaporize the burner fuel, the surface of the vaporizer and the proximity to the flame may be different for such different conditions.

A vaporizer remote from the burner may be employed either heated indirectly from burner heat supply or from an entirely separate heat source other than the atmosphere. Other differences between the embodiment of FIG. 1 and FIG. 9 will be apparent from the descriptions.

Referring particularly to FIG. 1 and FIG. 7, this fogger is started as follows. The fog material valve 184 should be closed. When the pump 134 has been started and the water valve 142 has been opened, water under pressure will be supplied to the fuel tank 156 through the outlet connections 144, 158, and valve 160 which should be open. The water pressure is indicated by the gauge 148 and may for instance be in the vicinity of 60 p.s.i. This approximate pressure is maintained by the proper adjustment of the pump by-pass valve 152. This pressure

is also exerted on the fuel 162 in the tank 156. The priming valve 66 is then opened and fuel flows through the pressure regulator 170 which may be set to maintain a pressure of for instance 40 p.s.i. as indicated by the gauge 172. Fuel will then flow into the generating pan 62. This fuel is then lit from an external flame and burns heating the vaporizer coil 50. When this is sufficiently hot, which may be in a matter of three to five minutes, the burner may be turned on. It may be mentioned that during generation of the burner, the cover 26 may be open. Operation of the pump 134 also supplies water at the pressure indicated by gauge 148 to the vaporizer 45. A quick connector fitting similar to that shown in FIG. 4 is mounted on the end of the vaporizer 45. This is provided with an orifice similar to the orifice 78 but generally somewhat smaller which controls the water supply to the vaporizer. The amount of water passing through this orifice is determined by the size of the orifice and the pressure differs on opposite sides thereof. The water flows through the vaporizer 45 through the outlet ends 44 and 47 through the steam orifice 86 and out the hollow threaded member 84. The burner valve 68 is now opened slightly and the burner starts. After the vaporizer 50 has been additionally heated by the burner flame, the burner valve 68 is opened to the proper operating burner setting which may be for instance 3½. It should be mentioned that the priming valve 66 may be closed except for maintaining the priming fire during burner generation. The burner flame during preferred operation may be bluish-yellow and does not extend substantially further toward the outlet than the larger diameter turns of the vaporizer. It is desirable that combustion should be completed toward the inlet end of the combustion duct formed by the inner lining 38. The burner is adjusted to maintain the desired steam pressure in a manner similar to that described in connection with the embodiment of FIGS. 9 and 19 and a similar steam gauge may be provided for this purpose. The proper burner operation can also be determined by adjusting the temperature to keep the issuing steam jet dry and to provide a fairly uniform pressure in the vaporizer. If pressure fluctuations occur, these can be detected by the sound. However, a steam gauge is desirable. The water pressure as shown by the gauge 148 can be kept reasonably constant by means of a properly constructed and regulated by-pass valve 152. However, better pressure control can be obtained with an additional pressure regulator which may be inserted in the connection 146. A single pressure regulator in the line 144 may also be employed to regulate both the water and fuel pressure. However, this would require the use of the same pressure on the water supply to the vaporizer and the fuel supply to the burner. It has been found that under certain conditions a lower pressure on the fuel to the burner is desirable. When a uniform flow of dry, preferably superheated, steam has been established from the opening in the threaded member 84, the fog oil or formulation valve 184 may be opened. Steam passing through the steam orifice 86 expands, entrains fluid in the space 104 and forms a vacuum in this space which is communicated to the annular space 102 to the interior of the tube 92 to the interior of the tube 94 through the tube 72 and the quick disconnect fittings 76, the flexible connection 188, the strainer 186, the valve 184 and the pipe 182 projecting close to the bottom of the fog material tank 178. When the valve is closed, a vacuum is produced within these passages which may be from 18 to 24 inches of thereabouts. A vacuum of 20 inches is satisfactory under certain circumstances of operation which have been carried out. When the valve 184 is opened, fog oil is drawn from the tank 178 by the path previously described to the annular clearance space 104. Here it is picked up by the issuing steam jet finely atomized and discharged as a thermal aerosol

out the opening in the threaded member 84. In passing through the round opening 110 in the air tube cover 120, air from the inside of the air tube is entrained, thus creating a flow of air into the air tube opening 112 and out the opening 110. The jet issuing from the outlet opening 42 of the nose or outlet cone 16 also augments the flow of combustion gases and air established by the burner in the duct within the inner lining 14. The air tube prevents overheating of the formulation in the nozzle body 82 and the tube 92 and functions in a way similar to that described in connection with the operation of the embodiment of FIG. 9. It will be noted that the nozzle and air tube assembly 32 is located further back from the outlet end of the outlet cone 16 than the corresponding parts shown in FIG. 9. The location of the jet nozzle further from or closer to the outlet of the cone 16 may considerably influence the operation. For instance, more heating of the fog oil by the hot combustion gases occurs with the jet nozzle further from the outlet. However, if the temperature of the combustion gases is high and a high rate of inflammable fog oil delivery is employed, there is a possibility of fog oil ignition. This tendency appears to be reduced at least under some circumstances by positioning the jet 25 nozzle closer to the nose outlet as shown in FIG. 9 and FIG. 16.

Referring now to FIG. 8, this shows a diagrammatic view of an embodiment of the invention in which similar numbers indicate the corresponding parts except that a 30 prime has been added to the numbers. The fogger 10 of this embodiment may be the same as shown in FIG. 1 and the fog material tank line and nozzle may be the same as in the previous embodiment. However, the tank 139' may contain for instance No. 2 furnace oil, No. 1 35 furnace oil, or a mixture of the two. The contents of this tank constitutes fuel for the burner as well as the liquid supplied to the vaporizer through the connecting member 146'. The No. 1 oil is better for burner, but does not form as dense a fog as No. 2 oil. The burner, 40 however, will operate although with a yellower flame on the No. 2 oil. The pump 134 may be operated in the same manner described in the previous embodiment or by other means. The starting, adjusting and operating are similar to that previously described. However, a 45 different burner setting may be required and a different diameter of orifice to determine the amount of oil delivered to the vaporizer 45. If the fog material does not contain, for instance, dissolved insecticide sensitive to heat, the fog material tank and feed line may be completely dispensed with and the fog produced entirely by 50 the jet of vaporized oil or other fog-forming fluid issuing from the steam orifice 82. This arrangement would be especially suitable for producing obscuring fogs for military purposes or fog to prevent freezing for instance in orchards. However, where a heat sensitive insecticide or 55 other material is to be distributed by the fog, its passage through the vaporizer can be avoided by providing a fog material containing a high percentage of insecticide in the tank 178' which passes through the valve 184', the strainer 186', the line 188', the tube 72', the tube 92', 60 the annular passage 102 and the annular clearance 104, and is sucked in and entrained by the oil vapor jet from the orifice 82. In this form of operation, the insecticide is all contained in the fog material in tank 178' and is mixed with the pure oil vapor from the tank 139' in the opening in the threaded member 84 and in the jet beyond. With this form of operation, the vaporized oil 65 issuing from the orifice 82 dilutes and enhances distribution of the insecticide and may persist longer in the atmosphere and carry greater distances than when water is employed. The use of water or oil in the vaporizer to produce the atomizing jet each have their particular advantages. The use of oil supplied to the vaporizer to 70 produce the atomizing jet may also be employed in the embodiment of FIG. 20 in which case an appropriate

oil would be substituted for the water in the tank 508. When an inflammable oil such as No. 2 furnace oil is used in the vaporizer to create the fog jet, there is more likelihood of ignition of the fog at the fog outlet 42 than when water is employed in the vaporizer. This tendency can be reduced by controlling the temperature, the position of the jet nozzle with respect to the fog outlet, and by other means. Also, this difficulty can be completely eliminated by employing the type of fog outlet and jet nozzle shown in the modification of FIG. 8a. The outlet end of the fogger 10 is provided with an upturn combustion gas outlet housing 600. The hot combustion gases pass in a horizontal direction from the duct formed by the inner lining 38 into the housing 600 and are discharged upwardly from the open top 602 of this housing. The end 47 of the vaporizer 44 projects through a hole 604 in the housing 600. The jet nozzle 606 may be similar to that shown at 82, 84, etc. in FIG. 5 or to that indicated by the numbers 426, 430, 436, etc. in FIGS. 16, 17 and 18 except that the air tube 424 is here unnecessary because the combustion gases are deflected upward and do not pass over the nozzle 606. This nozzle is located at a sufficient distance from the hot gas outlet 602 so that no ignition of the jet from the nozzle 606 can be produced by the hot exhaust gases issuing from outlet 602. The fog oil or formulation is supplied through the tube 72 and 92 to the annular clearance space 104 for instance as shown in FIG. 5. Although the arrangement of FIG. 8a is advantageous for the purpose of preventing fog light up, especially when the fog jet is produced by oil supplied to the vaporizer, it does not provide certain of the advantages which are obtained by mounting the jet nozzle in the outlet cone as shown in other figures, such as FIGS. 5 and 16. One of these advantages is the use of the hot flue gases for additional vaporization of the fog oil. The heat contained in these gases is wasted in the embodiment shown in FIG. 8a. Another advantage which this embodiment sacrifices is the injector effect of the jet issuing from the jet nozzle in augmenting the flow of hot gases initiated by the burner through the duct around the jet and out the fog outlet. This effect is quite advantageous for stabilizing the operation of the burner. With the jet outlet arrangement shown in FIG. 5 or FIG. 16 the action of the burner is almost entirely independent of external wind conditions due to the augmented flow of the hot gases produced by the jet. With the upturned outlet of FIG. 8a operation in a high wind or at a high vehicle speed may be somewhat erratic. Further, if oil is used instead of water in the vaporizer, the oil is still consumed and fogging cannot be stopped by closing the fog material valve 456. However, if propane is employed as burner fuel as in FIG. 19 or FIG. 20 when oil is supplied to the vaporizer 318 or 45', then fog may be shut off by closing the burner valve 354 to put out the fire and then closing the valve 142' to stop oil supply to the vaporizer. Fogging is resumed by reopening the burner valve 354 whereupon the pilot light 360 relights the fire. The valve 142' is then also opened. On the other hand, the burner of FIG. 1 and FIG. 8 requires generation to relight except for brief fire stoppage. It will thus be seen that the embodiment shown in FIG. 8a may be more or less advantageous, depending on the particular use and type of operation desired.

Referring again to the operation of the fogger on propane or L.P.G. as illustrated in the embodiments of FIGS. 19 and 20, it should be noted that L.P.G. is a cheap and advantageous fuel which is quite widely available in the United States. In some areas, L.P.G. is substantially cheaper than gasoline or even diesel fuel. It is also advantageous in that it may not require heating of a vaporizer prior to lighting of the burner. The burner may also be turned on and off at will and will relight from the pilot light. The pressure under which propane for instance is stored is also sufficient to deliver the fuel 75 desired air flow through the combustion space, pre-

to the burner and also water to the vaporizer, thus eliminating pumps and the power required to operate them. However, L.P.G. fuels must be stored in pressure-resistant containers. These are more expensive than a kerosene or fuel oil tank. Also, kerosene and fuel oil are more widely obtainable than L.P.G. In fact, in many places in the world where foggers are used L.P.G. is not obtainable at all or would be prohibitively expensive. It will thus be seen that the embodiment of FIG. 1 may be required in some circumstances while the embodiment of FIG. 9 is advantageous in others.

As previously stated, FIG. 21 illustrates an improved modification of the general type of fogger shown in FIG. 9.

The complete fogger unit 610 is provided with an outer shell 611. This is supported on two A-frames 612 and 613. Inside the outer shell 611 is an inner shell 614, there being a passage for combustion air 615 between the shells 611 and 614. Inside the shell 614 is an inner liner 616, supported by its flanged ends 617 and 618 on the shell 614. The vaporizer coil 619 is in turn supported on four longitudinal beads 620, pressed inwardly into the inner liner 616, as best shown in FIG. 22. The A-frames 612 and 613 are held together by the shelf 621 at the bottom and by the handle member 622 at the top. The outer shell 611 is held securely at each end in closely fitting bores in the A-frames. A burner cover plate 623 is secured to the A-frame 613 by screws and is spaced away from the A-frame about $\frac{1}{16}$ " by washers or depressions so as to provide an air space 624 between the cover and the A-frame. This is to provide an anti-resonance air passage. As will be seen in FIG. 22, the A-frames are provided with a series of lands 625, the inner ends of which constitute the bore which locates the inner shell 614. Between the lands 625 are air openings 626 which, when the pressure inside the combustion chamber 627 is reduced by the action of the burner 628 and by the ejector action of the jet nozzle 629, permits the passage of air from the A-frame 612 through the passage 615, through the space between the lands in the A-frame 613 and thence 40 between the end of the shell 614 and the cover 623 into the combustion chamber 627, and thence out the fog outlet 630. This provides an inflow of air from left to right in the opposite direction from the flow of air 45 through the combustion chamber from right to left and preheats the combustion air before its entrance into the combustion chamber; thus reducing heat losses from the combustion chamber and also cooling the exterior. A baffle washer 631 having a central hole 632 slightly larger 50 than the burner 628 is attached to the flange 618 and is thus spaced somewhat to the left of the burner 628. A six-point star-type baffle 633 is supported on the inner side of the coils of the vaporizer 619. The baffle and its elements are desirably made of heat-resistant material, for instance, high nickel and chromium alloy steel or chromium steel alloy. This baffle may be composed of three star-shaped discs 634, each disc having six equally-spaced slots 636 and six equally-spaced cutouts 55 between the slots. Each of the six slots in each disc is engaged in one of three slots in each of six spacer strips 635. When the three discs each having six slots are assembled with the six strips, each having three slots engaged in interlocking relation, a paddlewheel structure 60 is formed which, when inserted into the turns of the vaporizer, holds itself together; the strips 635 spacing the discs 634 a fixed distance from the inner surface of the vaporizer 619. A rod 637 engages a hole in one of the strips 635. The other end of the rod 637 passes through a hole in the baffle washer 631 and is secured to it by a thread on the end of the rod and a nut on each side of the baffle washer. This spaces the star baffle 633 the proper distance from the burner 628 to provide, together with the flow resistance of the baffle, 65 desired air flow through the combustion space, pre-

venting passage of flame to the vicinity of the nozzle and tending to maintain more uniform steam pressure. The burner 628 being located in the inside of the combustion chamber 627 is provided with a spark igniter 638 for lighting the propane gas when admitted to the burner. The proper voltage is applied to the igniter 638 through the spark coil 639 and the cable 640. The burner 628 constitutes the ground side of the spark gap. The motor pump unit 641 is mounted together with the coil 639 on the plate 621. The pump 642 supplies water or other vaporizable liquid to the vaporizer 619. Superheated steam is formed in the vaporizer which is discharged as a jet through the nozzle 629 ejecting steam, hot combustion gases, and fog formulation out the fog outlet 630.

The various connections, fluid and electrical, will be described more fully in connection with FIG. 23. The fog formulating material is admitted through the formulation line 643 and passes into the connecting tube 644, passing through the two A-frames 612 and 613 and the handle member 622. The other end engages the connecting elbow 645, the other end of which is connected to the nozzle feed tube 646. The tube 646 passes through the air jacket tube 647 which is welded or otherwise secured to the nozzle body 629. The air jacket tube 647 is also welded to the large diameter fog outlet tube 648. The nozzle body 629 with air jacket tube 647 is inserted into the outlet tube 648 by means of an elongated slot 649 which permits its insertion when slanted. After insertion, the nozzle body 629 is held concentric with the inner bore of the tube 648 by means of a jig as accurate centering of the nozzle in the tube 648 is desired. It is also important that the nozzle body 629 be located at the proper distance from the end of the fog outlet tube 648 so that the multiple jet discharge from the jet nozzle 629 passes out of the fog outlet 630 closely adjacent to its periphery. Preferably the axial distance of the discharge end of the nozzle body 629 from the opening 630 should be greater than the diameter of the tube 648. The tube 647 is then welded into the tube 648 and the elongated opening 649 is welded shut. The outlet tube 648 is connected to the inner shell 614 by means of a split conical member 650. The left end of the conical member 650 is positioned in a groove 651 in the tube 648. The split ends of the conical member 650 are then connected together by screws and the large end of the conical member 650 is a sliding fit inside the inner shell 614. The split nose member 652 is secured to the inner shell 614 by means of an annular groove 653 which embraces a small flange on the left end of the inner shell 614. The split in the nose member 652 is then clamped together by means of the clamping screws 654 so that the split hole 655 surrounding the air jacket tube 647 is tightly located in position. The left end of the nose member 652 fits tightly around the outer diameter of the tube 648 and is positioned in an axial direction by the close fitting hole 655 through which the air jacket tube 647 passes. This construction permits the ready assembling and disassembling of the unit composed of the tube 648 and nozzle body 629. The right end of the nozzle body 629 is threaded to receive the union nut 656 which attaches it to the left end of the vaporizer coil 619. A bolt 657 passes through the inner liner 616, the inner shell 614 and the A-frame 612 which locates these units axially at only one point, thus permitting free axial expansion and contraction of the heated members.

If desired, perforated outer casing 658 extending downward to the shelf 621 may be added for appearance and protection. Also the cover member 659 may be employed to cover the split in the nose member 652 and the clamps and clamping screws 654.

The fog outlet tube 648, the nozzle body 629, and the various component parts and detailed construction of the inner nozzle members are best shown in FIGS.

24, 25 and 26. The nozzle body 629 is composed of four sections welded together. The strainer compartment 660 has a larger bore to permit passage of steam outside the strainer 661. The strainer compartment is welded or otherwise attached as indicated at 662 to the right-hand member of the split sleeve 663, the left-hand member of which is 664. Each of the members 663 and 664 has a semicircular cutout into which the air jacket tube 647 fits. This permits the assembly of the air jacket tube into the nozzle body and it is welded or otherwise attached to the nozzle body as indicated at 665. The overlapping joint between the sleeves 663 and 664 forms a substantially air-tight joint between them. However, prior to the assembly of parts 663 and 664 of the nozzle body, the nozzle feed tube 646 is welded into the nozzle body inner member 666. This member fits into a bore in the strainer compartment 660 and also fits the inside bore of the sleeve 663. When these outer nozzle body parts are assembled around the inner nozzle body, the air jacket tube 647, the fuel feed tube 646, and the nozzle body parts form the nozzle body unit 629. The inner nozzle body 666 is provided with a tapered seat 667 and with an internal thread 668 connected by a slightly larger bore. The steam nozzle 669 has a flange 670 which engages the seat 667 to form a steam-tight joint. The right end of the steam nozzle 669 carries the steam strainer 661. This is composed of perforated or screen material and is provided with a perforated or screen abutment 671 to trap scale or solid material larger than the perforations. Thus the strained-out solid material is trapped inside the steam strainer 661 while the steam may pass out of the strainer 661 and in again on the other side of the perforated abutment. The strainer 661 is secured to the steam nozzle 669 by means of a snap ring 672 having an inwardly turned end which passes through a hole in the strainer 661 and through a corresponding hole in the strainer end of the steam nozzle, thus locking the strainer to the steam nozzle. The steam nozzle has six steam bores 673, each having equal angular separation from the other. The axis of these bores makes a 15° angle with the central axis of the steam nozzle 669. Between these bores are six formulation bores 674, one midway between each pair of steam bores 673. These feed formulation from the annular formulation passage 675 to the formulation entrainment space 676. Thus the liquid formulation enters through the nozzle feed tube 646, thence into annular space 675, thence through the six formulation bores 674 into the entrainment space 676. There it is picked up and entrained by the steam jets. A multiplicity of bores is desirable as it provides a longer line of contact between the periphery of the steam jets and the fog oil flowing inward toward the jets than if a single larger bore was employed. However, with multiple jets, uniform distribution of fog oil to each jet is desirable. Leading the formulation inward to the center of the entrainment space 676 through the inwardly directed formulation bores 674 introduces the formulation in a central position equidistant from the outlet of each steam bore 673 and the corresponding inlet of each bore 678. This is favorable to uniform distribution. It has been found that good suction and entrainment is secured when the diameter of the steam bore 673 is about 70% of the diameter of the outlet bore 678. The outlet nozzle member 677 also has six equally-spaced bores 678, each coaxial with its corresponding steam bore 673. The bores 678 also have considerable axial length which tends to increase the nozzle suction and maximum fogging rate. The outlet nozzle member 677 is provided with an external thread 679, corresponding with the internal thread

668 in the inner nozzle body 666. It is also provided with hex flats 680 for assembling and disassembling. In addition, the outlet nozzle member is also equipped with two oppositely positioned tongues 681 which engage corresponding slots in the steam nozzle 669. These provide axial alignment for the bores 673 with the bores 678. These tongues and slots are annularly grooved to take a snap ring 682, which holds the assembly of the steam nozzle and outer nozzle together so that they can be put in and taken out of the inner nozzle body 666 as a unit. The bores 678 may be given an outward taper as shown if desired. The upper end of the air jacket tube 647 is crimped inwardly in three places so as to maintain concentricity with the nozzle feed tube inside it. Outside air enters the space 683 between the air jacket tube and the nozzle feed tube 646. This passes down into the annular space 684 surrounding the inner nozzle body 666 and is sucked out the annular orifice 685 by the ejector effect of the jet nozzle discharge. This flow of cool air through the air jacket around the nozzle 629 prevents overheating of the fog oil or formulation in the jet nozzle 629. It has been found that in hot weather when the temperature of the fog oil or formulation is high that the rate at which formulation can be drawn from the tank 691 by the suction of the jet nozzle 629 is substantially reduced unless the jet nozzle is cooled. The air-cooling jacket maintains satisfactory fogging rate in the highest temperatures encountered in southern summer weather. It is desirable to maintain certain relations between the diameter of the outlet tube 648, the angle of the jet discharge 686, and the distance between the end 687 of the outlet tube 648 and the point of intersection 688 between the jet discharge axis 690 and the axis 689 of the nozzle. This relation should be such that the axis of the jet discharge 690 should just clear the inner bore of the outlet tube 648. If the axis of the jet 690 is too far out from the axis 689, formulation will strike and accumulate on the end of the exhaust nozzle 648 and may cause dripping. If the axis of the jet 690 reaches the end of the outlet tube too far inward towards the central axis 689, then there is more likelihood of light up. The multiple jets discharging toward the periphery of the outlet tube also provide a better ejector effect and a longer and more intimate contact of the fog oil or formulation with the hot combustion gases. This effect is also enhanced by positioning the jet nozzle 629 further back within the fog outlet tube 648 so that there is longer mixing and contact time before reaching the fog outlet 630. The resistance to light up and the ejector effect are satisfactory with the relations shown.

The fluid and electrical connections to the fogger 610 are best shown in FIG. 23 and will now be described.

The fog formulation is contained in the tank 691 and may pass through a strainer 692, into the flow meter 693, thence through the flow control valve 694 to the formulation line 643 and the connecting tube 644, and thence to the jet nozzle 629. The flow meter 693 may be of transparent material with a scale, for instance in gallons per hour. It may have an inside passage expanding from bottom to top and be equipped with an indicator which rises upward against the force of gravity as the formulation flow increases with further opening of the control valve 694. Thus, by adjusting the flow control valve to the desired reading on the flow meter, a predetermined quantity of fog may be put out.

In a similar manner, water is supplied to the pressure pump 642 from the water tank 696, through the strainer 697, and the water intake line 698. A liquified gas, such as propane, is contained under its own pressure in the fuel tank 699. This passes through the shut-off valve 700 when open, and through an excess flow valve 701 into the gas line 702. In the event of a breakage in the gas line, the excess flow valve limits the rate of flow of propane gas from the break to an amount not

greatly in excess of the maximum flow required for normal operation, and is thus purely a safety device.

The fogger 610 may be mounted on a vehicle, as for instance a truck or vehicle 128 shown in FIG. 7. The 5 formulation tank 691, the water tank 696, and the propane fuel tank 699 are also carried by the vehicle 128.

The electrical system 703 of the vehicle 128 supplies the electrical energy to operate the electric motor 704 which drives the water pump 642, and also the electrical energy for the other devices shown in the diagram of 10 FIG. 23. The generator 705 is part of the electrical equipment of the vehicle and is driven by means of the belt 706 from the engine of vehicle 128, not shown. The storage battery 707 and the voltage regulator 708 15 controlling the charging rate of the battery with varying speed of the generator 705 are also part of the electrical system 703 of the vehicle 128.

When the fogger 610 is in operation but not producing fog, the motor 704 drives the pump 642, drawing water 20 or other vaporizable liquid from the tank 696, and delivering it under pressure to the water line 709. This water under pressure passes into the pressure control bypass valve 710 and the pressure is registered on the water gauge 711. A portion of the water flow is directed through the 25 water flow control orifice 712. This is a small hole of such size as to permit the desired flow of water therethrough to the vaporizer inlet 713, said inlet of the vaporizer coil 619 being also indicated by the number 713 in FIG. 21, when the water pressure is maintained at the 30 appropriate predetermined value by the pressure regulator 710. From the vaporizer inlet, the water passes into the vaporizer coil 619 where it is converted into superheated steam by the heat of the burner 628. The burner is supplied with gas from the gas line 702 through the 35 pressure regulator 714. This is adjusted by means of the handle 716 to maintain the proper gas pressure indicated by the gauge 715. From the pressure regulator 714, the gas flows into the automatic control unit 717. When the starting button 718 is manually depressed, gas flows to the 40 burner through the gas cut-off valve 719. Depressing the button 718 also supplies all electricity to the pump motor 704 and to the burner ignition coil 639 which produces a spark from the igniter 638 to the end of the burner 628. The starting button 718 is held down manually until a 45 predetermined steam pressure is generated in the vaporizer coil 619 and indicated on the steam gauge 720. When this predetermined pressure is communicated to the pressure responsive latch diaphragm 721 through the diaphragm steam connection 722, the diaphragm 721 moves 50 upwardly and the latch 723 engages the collar 724 on the stem of the gas cut-off valve 719. Manual pressure may then be removed from the starting button 718 and still the latch 723 will maintain the valve 719 open and the power supply contacts 725 closed. However, the ignition contacts 726 which are not latched will then open, cutting off 55 the ignition which is no longer needed as the burner is in operation. As long as the steam pressure in the vaporizer 619 does not fall below a predetermined value, the burner 628 and the motor 704, driving the pump 642, will continue to operate. Also if the remote control switch 727 with its fog-on pilot light 728 is closed, the fog on-off solenoid coil 729 will be energized and the fog on-off valve 730 will be closed, thus preventing the flow of air 60 into the fog connecting tube 644 and producing a vacuum therein as a result of the ejector effect of the discharge of steam from the jet nozzle 629. This draws fog oil or 65 formulation material from the tank 691 and discharges it together with the steam through the fog oil passages in the nozzle 629, as described in connection with FIG. 24. If as the result of any malfunction which causes the steam 70 pressure applied to the diaphragm 721 to fall below the predetermined value, the latch 723 will be disengaged from the collar 724 and the spring 731 will close the gas valve 719 and open the contact 725. This cuts off the gas 75 supply to the burner 628 and current to the pump motor

704. It also deenergizes the solenoid coil 729 and the spring 732 opens the fog on-off valve 730, thus admitting air to the connecting tube 644 and preventing fog oil or formulation from being raised from the tank 691, which is located below the valve 730, which when open admits air freely and reduces the suction to a negligible value. It is desirable to cut off the supply of fog oil to the jet nozzle 629 as soon as or before the discharge of steam from the nozzle 629 ceases, because inflammable fog oils may ignite at the nozzle 629 unless steam is being discharged therefrom. It will be seen that if the switch 727 is opened during the operation of the fogger only the coil 729 is deenergized, opening the valve 730 and cutting off the fog. The discharge of steam from the jet nozzle 629 continues but, due to the fact that the steam is superheated, it is transparent and the effect is simply to discontinue the flow of fog which can be immediately resumed by merely closing the switch 727, thus providing a quick acting fog on-off control which may be located in the cab of the vehicle 128 close to the hand of the driver.

Operation of the fogger 610 may be stopped completely by pressing the stop button 733. This releases the latch 723, closing the gas valve 719 and opening the electric current supply contacts 725. Pressing the stop button 733 contracts and depresses the diaphragm 721 against the steam pressure which holds it open. If the steam pressure falls below the predetermined point, the spring 734 releases the latch 723 against the action of the latch spring 735. The operation of the fogger 610 is then completely stopped until the starting button 718 is again manually depressed to restart.

The pump 642 normally supplies an amount of water in excess of that passing through the water orifice 712 into the vaporizer inlet 713, the excess water is by-passed through the line 736 and the water return line 737 back to the water tank 696. However, if the jet nozzle cooling valve 738 is opened, a certain amount of this water will be delivered through the open valve 730 to the connecting tube 644 and thence to the jet nozzle 629, following the same path as taken by the fog oil. When the valve 730 is open, no fog oil flows and the jet nozzle 629 tends to become hotter than when fog oil is flowing and fog is being put out. Under conditions of extreme heat and when fogging at a low rate, normal fogging can be more quickly resumed after a considerable period of fog interruption if during the interruption a small flow of water from the valve 738 is delivered to the nozzle 629. It will be noted that the water used for this purpose is taken from that portion of the water supply which is normally returned to the tank and that this arrangement supplies a relatively fixed water level from which a uniform amount of water can be drawn by the appropriate adjustment of valve 738.

It may be mentioned here that if desired the latch diaphragm 721 which has previously been described as connected to the vaporizer inlet 713 through the connection 722 may be operated from the water pressure in the water line 709 instead of by steam pressure. If operation by water pressure is desired, the connection 739 shown in dotted lines may be made between the water line 709 and the connection 722 to the diaphragm 721. This also requires the line 722 to be disconnected from the steam supply from the vaporizer inlet 713. Satisfactory operation may be had by applying water pressure to the diaphragm 721 instead of steam pressure. However, certain additional protection is provided by the operation of the diaphragm 721 by steam. There is, however, a different advantage by operating the diaphragm 721 by water pressure which is that the water pressure is more constant, where the steam pressure may, under certain circumstances, fluctuate periodically which might cause the control automatic to stop operation of the fogger when nothing was wrong except an unusually large steam pressure fluctuation. This can be guarded against by so adjusting the response of the diaphragm 721 so that the

steam pressure must fall to a low value before the automatic operates. The water system is relatively free from such pressure fluctuations.

The operation of the embodiment shown in FIGS. 21, 22, 23, 24, 25 and 26 will now be described.

The fogger unit 610 may be mounted on an automotive surface vehicle with the fog outlet 630 pointing generally to the rear. The formulation tank 691, the propane fuel tank 699, and the water tank 696 are carried by the automotive vehicle and connected to the fogger 610 as shown in diagrammatic FIG. 23. The electrical connections of the pump motor 704 and connections to the other electrically operated components are made to the generator battery system 703 of the automotive vehicle 128. To get up steam preparatory to fogging, the gas fuel valve 700 is first opened. Then the handle 716 of the pressure regulator 714 is turned inward until the pressure gauge 715 reads, for instance, 15 p.s.i. The starting button 718 is then pressed down and held manually. This opens the gas cut-off valve 719 supplying gas to the burner 628. It also closes the contacts 726 supplying the ignition spark to the burner. The switch 725 is also closed supplying current to the pump motor 704 and in fact to all of the electrically operated components. Water is then pumped from the water tank 696 by the pump 642 and forced into the vaporizer 619 by the water metering orifice 712. The burner is now lit and steam is generated in the vaporizer 619 and registers on the gauge 720. It is also supplied to the diaphragm 721 through the connection 722. The handle of the pressure regulator 714 is then turned further in until the pressure on the gas pressure gauge 715 indicates, for instance, 35 to 40 p.s.i. This increases the burner flame and steam, at first wet and then superheated, issues from the nozzle 629. The pressure under the diaphragm 721 also increases so that after less than a minute of operation the expansion of diaphragm 721 engages the latch 723 with the collar 724, thus locking the gas valve 719 in open position and maintaining the contacts 725 closed. The finger may now be removed from the starting button 718 and the fogger is now in operation maintained automatically as long as steam pressure under the diaphragm 721 is above a predetermined value. When the steam pressure on the gauge 720 rises to, for instance, about 30 p.s.i. and superheated steam, which is colorless, issues from the nozzle 629, fogging may be commenced. This is done by closing the switch 727 which lights the lamp 728 indicating fog on and energizes the solenoid coil 729. This closes the fog on-off valve 730 and fog material or formulation is sucked from the tank 691, through the connecting tube 644, into the annular formulation space 675, through the supply tube 646, and thence through the formulation bores 674, and formulation entrainment space 676, and out the outlet bores 678, as the result of the ejector effect of the steam issuing from the steam bores 673. This also creates a suction in the air jacket space 683, which causes a flow of cooling air out the annular air space 685. The ejector action of the jets discharging along the jet axes 690 also induces an additional flow of air from the air intakes 626 through the combustion chamber 627 and out the fog outlet 630. The rate at which fog oil or formulation is discharged from the fog outlet 630 is determined by the setting of the flow control valve 694 and is indicated by the flow meter 693 which may indicate a formulation flow of for instance 40 gallons per hour. Fogging at this rate will then continue until the fog on-off switch 727 is opened. This will open the fog on-off valve 730 and stop the flow of formulation. However, the flow of steam will continue and the fogger will continue to operate but without any discharge of fog. It may be mentioned at this point that in FIG. 21, a horizontal type of fog on-off solenoid valve is shown. In this type, the coil 729 may surround a solenoid plunger which carries the valve 730 and is normally raised off its seat by a spring and closed by the energization of the coil. This horizontal solenoid is not shown in detail but acts

in the same way as the solenoid valve 730 shown in FIG. 23.

By again closing the switch 727, fogging is immediately resumed. Thus, fogging can be interrupted and resumed very quickly and easily by manual operation of the switch 727 located near the hand of the automotive vehicle driver.

If any of the following conditions develop, the steam pressure applied to the diaphragm 721 will be reduced and the spring 734 will press the member 733 downward and unlatch the latch 723 from the collar 724. This cuts off the gas supply by closing the valve 719 and opens the contact 725 which cuts off the supply of electricity to all the electrically operated apparatus, including the fog on-off valve 730 even when the switch 727 is closed. These various actions completely shutting down the fogger will occur:

(1) If any interruptions of the main electrical supply takes place, the motor 704 will stop, thus stopping the pump 642 and reducing the steam pressure applied to the diaphragm 721 as soon as water in the vaporizer coils 619 is exhausted. However, as soon as an interruption in the electrical supply takes place, the fog on-off valve 730 will open and the supply of fog oil or formulating material will cut off and fogging will cease substantially before the steam pressure drops. This is desirable to prevent discharge of fog oil when steam pressure is low and ignition of fog oil might take place.

(2) If the supply of water in the tank 696 is exhausted, water will then no longer be supplied to the vaporizer and the steam pressure will fall and the device will automatically stop. The same result will occur if the motor 704 or the pump 642 ceases to function and no more water is supplied to the vaporizer 619. The same action will also occur if there should be a plugging of the water orifice 712 or if the water strainer 697 should become plugged. In the event that there should be a blockage in the propane gas supply, for instance in the line 702, or if the supply of propane fuel became exhausted, the burner 628 will go out or burn too low to maintain the necessary steam pressure on the diaphragm 721 and automatic stoppage on the whole system will again occur. In fact, anything that causes failure of the water supply, the gas supply or the supply of electrical energy, will cause the automatic complete shut down of the fogger and this constitutes a very desirable safety feature.

If it is desired to stop complete operation of the fogger when it is functioning normally, this may be done by pressing down the stop button 733 which operates the latch 723 and effects stoppage in the same way as the automatic stoppage due to malfunction previously described. When the diaphragm 721 is operated by steam pressure, complete stoppage of the fogger can be effected without the use of the stop button 733 by cutting off the supply of gas fuel by means of the valve 700 on the propane tank, or by turning the handle 716 all the way out so that the pressure regulator 714 cuts off the gas supply. The fogger is then stopped in the same way as previously described when the gas supply is cut off through malfunction.

In the event that the diaphragm 721 is operated by water pressure through the dotted connection 739 instead of with steam pressure as previously described, automatic stoppage will occur in substantially the same manner if there is a failure in the electrical supply or a failure of the pump 642 or if water is exhausted in the tank 696. However, this will not effect stoppage if the water orifice 712 should be plugged, which is a very unlikely occurrence, or if the burner goes out, which is also very unlikely except when the gas is exhausted and in this case no damage would occur. Thus either the steam pressure or water pressure may be used to operate the automatic control depending on which is most suitable to the particular circumstances. With water pressure applied to the diaphragm 721, the fog on-off valve 730 will cut the

fog immediately upon failure of water supply and, therefore, the fog may be cut off quicker than with the steam operation of the diaphragm 721.

Based on the foregoing description and illustrations of my invention, I claim:

1. In a jet fogging system, an elongated generally tubular member communicating at one end with a source of heated gases, and having an opening to the atmosphere of substantially the inner diameter of the outlet end of said tubular member, a jet atomizing nozzle positioned concentrically with said tubular member and at an axial distance from said atmospheric opening greater, but not more than three times greater, than the diameter of said opening said jet atomizing nozzle comprising a casing, said casing having an inlet connected to a source of jet fluid under pressure and an inlet connected to a source of fog-forming liquid, at least one bore in said nozzle directed toward the periphery of the atmospheric opening in said elongated member and adapted to expand the jet issuing

from said jet atomizing nozzle toward the periphery of the atmospheric opening in said elongated tubular member, said bore communicating at its inner end with said fluid pressure inlet, and communicating at a point between the inner and outer end of said bore with said fog-forming liquid inlet.

2. In a jet fogging system, an elongated generally tubular member communicating at one end with a source of heated gases, and having an opening to the atmosphere of substantially the inner diameter of the outlet end of said tubular member, a jet atomizing nozzle positioned concentrically with said tubular member and at an axial distance from said atmospheric opening greater than but not more than three times greater than said inner diameter, said jet atomizing nozzle comprising a casing, said casing having an inlet connected to a source of jet fluid under pressure and an inlet connected to a source of fog-forming liquid, a plurality of bores in said nozzle directed angularly outward and toward the periphery of the atmospheric opening in said elongated tubular member, said bores communicating at their inner end with said fluid pressure inlet, and communicating at a point between the inner and outer ends of said bores with said fog-forming liquid inlet whereby the discharge of pressurized fluid from said bores entrains fog-forming liquid within said bores and atomizes and mixes it with hot gases from said source in said tubular member to additionally vaporize said fog-forming material, and discharges each jet through and adjacent to the periphery of said atmospheric opening.

3. An aerosol fogging system comprising an atomizing nozzle having at least one bore through which pressurized fluid is discharged establishing a suction associated with said bore, a tank of aerosol-forming material, said atomizing nozzle being located at a level above the highest level of liquid in said tank, a passage extending from the lower portion of said tank to said atomizing nozzle through which aerosol-forming liquid is sucked up to and discharged from said nozzle, means for starting and stopping the flow of aerosol liquid to said nozzle, comprising means for opening or closing an air-admitting orifice in said passage at a point above the highest level of liquid in said tank, and electrically-operated valve means for closing to start and for opening to stop the flow of aerosol fog material to said nozzle, said electrically-operated valve means being manually operable from a remote point by electric control.

4. In a vapor generator having a boiler, a burner heating said boiler, a jet nozzle connected to said boiler and adapted to discharge a jet of vaporized liquid under pressure from said boiler, means for starting and stopping the flow of vaporizable liquid to said boiler, means for starting and stopping the flow of fuel to said burner, a source of vaporizable liquid and means communicating between said source and said starting and stopping means, a source of fuel for said burner and means communicating between said source and said starting and stopping means, a start-

ing member which when manually held causes the flow of fuel to said burner and vaporizable liquid under pressure to said boiler, locking means for maintaining said flows after manual holding stops, pressure responsive means connected to said boiler controlling said locking means so as to continue fuel flow to the burner, and vaporizable liquid to the boiler only when a certain predetermined pressure exists in said boiler, and effecting the unlocking of said locking means and automatically stopping the flow of fuel to the burner and vaporizable liquid to the boiler when the boiler pressure falls below and predetermined point.

5. In a fogger having a boiler, a burner heating said boiler, a jet nozzle connected to said boiler, a source of fog-forming material communicating with said jet nozzle and adapted to be entrained and discharged as a jet through said nozzle via the agency of vapor under pressure from said boiler, electrically-operated means for starting and stopping the flow of fog-forming material to said jet nozzle, a valve member for cutting off the fuel supply to said burner normally held closed, main electrical contacts associated with said fuel valve member so as to be closed when said fuel valve is opened and energizing the main electrical circuits, a starting button for manually opening said fuel valve member, burner ignition contacts closed when said button is manually pressed and open when said button is released, latch means for holding said fuel valve in open position with said main contacts closed, pressure responsive means communicating with said boiler controlling said latch means so that said fuel valve is latched open only when there is a certain predetermined pressure in said boiler and effecting the unlatching and closing of said fuel valve member and the opening of said main contacts when the boiler pressure falls below said predetermined value, electrical means operable when said main contacts are closed to supply vaporizable liquid under pressure to said boiler and manually operable electric contact means for stopping the flow of fog material to said nozzle when open and for starting the flow of fog material only when last said contacts are closed and said main contacts are also closed.

6. A fogger comprising a hot gas duct having a burner adjacent one end thereof, an opening at the other end, a jet discharge nozzle directing a vapor jet into the atmosphere through said opening, a coiled tube boiler supplying vapor to said nozzle between said burner and said opening, the combustion gases from said burner passing through the center of said boiler coil, and indirectly heating it baffle means for controlling the flow of combustion gases through said boiler coil induced by the ejector effect of said jet discharge nozzle and for preventing the combustion flame from reaching the jet discharge nozzle comprising a plurality of heat resistant disc members held in position by a plurality of rail members, said rail members contacting the inside of the boiler tube coils and spacing the periphery of said disc members at a predetermined distance therefrom, and means for positioning said baffle means at predetermined position within said boiler tube coil so as to control the flow of gases and restrict the combustion flame.

7. A fogger comprising a hot gas duct having a burner adjacent one end and an opening to the atmosphere at the other, a jet discharge nozzle directing a jet of hot atomized fluid into the atmosphere through said opening, a vaporizer in said duct between said burner and said jet nozzle supplying hot fluid under pressure to said nozzle, means for stopping and starting said burner, electrical means for igniting said burner, a manually operable starting member associated with said burner stopping and starting means, ignition contact means associated with said burner starting member adapted to stop said burner ignition when the manual operation of said starting member is discontinued, means responsive to pressure in said vaporizer for locking the burner stopping and starting means in the start position after manual operation of said

starting member is discontinued and after operation of said burner has generated a predetermined pressure in said vaporizer whereby the manual operation of said starting member starts and ignites said burner, and the discontinuance of said manual operation operates said ignition contact means to stop ignition, said burner being maintained in start position by said locking means as long as the burner maintains a predetermined pressure in said vaporizer.

10. A fog generating apparatus comprising an outer shell and an inner shell spaced from the outer shell to provide an air jacket around the inner shell, a burner mounted within the inner shell adjacent one end thereof, a jet nozzle mounted adjacent the opposite end of said inner shell and discharging fluid through an opening in said inner shell adjacent to said jet nozzle, an air intake in said outer shell adjacent said jet nozzle end, the opposite end of said outer shell being covered, an opening for the passage of air from said outer shell to said inner shell adjacent the burner end, means supplying hot jet discharge fluid within said inner shell connected to said jet nozzle and being heated by said burner, said jet nozzle discharging through the opening in said inner shell and producing an ejector effect which draws air through said air jacket in one direction and over said burner and over said jet fluid supply means in the opposite direction.

15. 9. A fog generating apparatus as claimed in claim 8 in which a small opening to the atmosphere is provided in the covered end of said outer shell to prevent an audible 20 resonance effect.

10. A fog generating apparatus comprising an elongated multi-wall housing including a multiplicity of spaced walls forming a central chamber and an air jacket surrounding said chamber, a burner in said central chamber 25 adjacent one end thereof, a jet discharge nozzle in said chamber adjacent the opposite end thereof, an opening to the atmosphere in said chamber at the jet nozzle end toward which the jet discharge from the nozzle is directed, a member covering the burner end of said housing, an 30 air passageway from said air jacket to said central chamber adjacent the burner end, the other end of said air jacket communicating with the atmosphere adjacent the jet nozzle end, a pressure-tight fluid passage heated by said burner within said central chamber between said 35 burner and said jet nozzle, means connecting said fluid heating passageway to said jet nozzle for the discharge of a jet of heated fluid from said passageway through said nozzle and out of the opening in said chamber to the atmosphere so that the ejector effect of said discharge 40 reduces the pressure in said chamber causing a flow of air from the jet nozzle end of said air jacket into the central chamber adjacent the burner end and out the opening in said central chamber to the atmosphere together with said jet nozzle discharge.

55. 11. In a jet atomizing system, an atomizing nozzle comprising a casing provided with a pressure fluid inlet, an atomizable liquid inlet, and a nozzle member recess, a first nozzle member insertable in said recess, said member having at least three fluid conveying bores communicating with said pressure fluid inlet and directed at an 60 outward angle therefrom, and at least three liquid conveying bores communicating with said liquid inlet and directed inwardly toward the center of said first nozzle member, each liquid conveying bore being positioned between two fluid conveying bores, a second nozzle member insertable in said recess and having at least three larger outwardly directed bores each coaxial with a corresponding fluid conveying bore in said first member and an entrainment chamber between said first nozzle member and said second nozzle member communicating with 65 all of the bores in both the first and second nozzle member.

70. 12. In a fogger having a boiler, a burner heating said boiler, a jet nozzle connected to said boiler, means for 75 supplying vaporizable liquid to said boiler, a source of

fog-forming material communicating with said jet nozzle so that the material may be entrained and discharged as a jet through said nozzle via the agency of vapor under pressure from said boiler, electrically operated means for starting and stopping the supply of vaporizable liquid under pressure to said boiler, fuel valve means for starting and stopping the fuel supply to said burner, a starter button which when manually pressed starts the supply of vaporizable liquid and opens said fuel valve, electrical burner ignition means to provide burner ignition when said starting button is manually pressed and to terminate electric ignition after said button is released, separately manually controllable electromagnetic means for starting and stopping the flow of fog-forming material to said jet nozzle, automatic means responsive to a predetermined pressure in the supply of vaporizable liquid to said boiler to maintain the supply of vaporizable liquid to said boiler, the supply of fuel to said burner and the supply of fog-forming liquid to said jet nozzle as long as said predetermined pressure is maintained and to stop the supply of said liquid to said boiler, said fuel to said burner and said fog-forming material to said jet nozzle when the pressure on said automatic pressure responsive means falls below said predetermined pressure.

13. A fog generator having a boiler, a burner heating said boiler, a jet nozzle connected to said boiler adapted to discharge a jet of vaporized liquid under pressure from said boiler, means for supplying vaporizable liquid under pressure connected to said boiler, means for starting and stopping the flow of vaporizable liquid thereto, means for supplying fuel under pressure to said burner, means for starting and stopping the flow of fuel thereto, a starting member which when manually operated starts the flow of vaporizable liquid under pressure to said boiler and the flow of fuel to said burner, means responsive to said vaporizable liquid pressure to maintain the flow of vaporizable liquid and fuel as long as a predetermined pressure in the vaporizable liquid supply means is maintained, said vaporizable liquid and fuel flow being stopped when the pressure on said vaporizable liquid supply means falls below said predetermined point, whereby said manually operable starting means must be again manually operated before the flow of vaporizable liquid and fuel can be restarted.

14. A fogger comprising a hot gas duct having a burner adjacent one end thereof, an opening at the other end, a jet discharge nozzle directing a vapor jet into the atmosphere through said opening, a coiled tube boiler disposed within said duct between said burner and said opening said boiler supplying vapor to said nozzle, the combustion gases from said burner passing into said boiler coil and indirectly heating said flow, baffle means for controlling the flow of combustion gases through said boiler coil induced by the ejector effect of said jet discharge nozzle, said baffle comprising a heat resistant, flame obstructing and gas flow directing structure axially to position said structure within said boiler coil to direct the hot gases outwardly over said boiler tubes and to prevent the combustion flame from reaching the jet discharge nozzle.

15. A fogger comprising a hot gas duct having a burner adjacent one end thereof, a boiler heated by said burner, a jet discharge means connected to said boiler discharging vapor from said boiler, means for supplying vaporizable

liquid to said boiler comprising an electric motor driving a pump, a connection from the outlet of said pump to said boiler, said connection including a small orifice limiting the flow of vaporizable liquid from said pump to said boiler and vice versa, an electric source, means for connecting said electric source to said electric motor to drive said pump, pressure responsive means in said connection between the pump outlet and said small orifice adapted to stop said motor and pump when the supply of vaporizable liquid to said pump is insufficient to maintain a predetermined pressure on said pressure responsive means, manually operable push button means for connecting and disconnecting said electric source from said electric motor adapted to maintain motor and pump operation only while said button is manually pressed or while said predetermined pressure is applied to said pressure responsive means, whereby when said push button means is no longer manually pressed the motor and pump operation continues as long as predetermined pressure is applied to said pressure responsive means and the motor and pump are stopped when the pressure falls below said predetermined pressure.

16. A fogger comprising a hot gas duct having a burner adjacent one end thereof and having an opening to the atmosphere of substantially the inner diameter of the outlet end of said duct, a jet discharge nozzle spaced within said duct a distance from said opening greater but not more than three times greater than the diameter of said opening to the atmosphere and directed toward said opening, a pressure resistant vapor-conveying passageway within said duct heated by said burner, at least one bore in said jet nozzle directed toward said opening to the atmosphere in communication with said vapor-conveying passageway, a fog material passageway in communication with said bore, said bore having a reduced diameter in the vicinity of said communication of said fog material passageway with said bore so that the increased velocity of vapor passing into and through said bore results in a suction being applied to said fog material passageway by aspiration, a source of fog material in communication with said fog material passageway, whereby fog material is sucked by aspiration from said source, atomized and discharged with the jet from said jet discharge nozzle and expelled from said opening to the atmosphere with the hot burner gases.
